Patented Dec. 28, 1920.

Glara V. Spavens. INVENTOR;
BY Deedersheen & Fairbank ATTORNEYS.

UNITED STATES PATENT OFFICE.

CLARA V. HAVENS, OF NEW YORK, N. Y.

GARMENT-FASTENER.

1,363,591.

Specification of Letters Patent. Patented Dec. 28, 1920.

Application filed August 14, 1920. Serial No. 403,465.

To all whom it may concern:

Be it known that I, CLARA V. HAVENS, a citizen of the United States, residing in the city, county, and State of New York, have 5 invented a new and useful Garment-Fastener, of which the following is a specification.

My invention consists of a garment fastener which is more particularly adapted to 10 securing a brassière to a corset, but to which, however, I do not limit the use of the same, the fastener being composed of a comparatively U or V-shaped member, and eyes on the arms thereof, one of said eyes being 15 adapted to have an attachment of the brassière permanently connected therewith so as to prevent loss of the fastener or disconnection thereof from said attachment, while the other eye is adapted to have another attachment of the brassière fitted thereto in a convenient manner, thus retaining the fastener on the corset and thereby connecting the brassière with the latter, while the second named attachment is easily removable from 20 the eye with which it is engaged, and so permitting the fastener to be removed from the corset.

The invention is satisfactorily illustrated in the accompanying drawing, but the important instrumentalities thereof may be varied, and so it is to be understood that the invention is not limited to the specific details shown and described, as long as they are within the spirit or scope of the claims.

35 Figure 1 represents a side elevation of a garment fastener embodying my invention.

Fig. 2 represents a longitudinal section thereof on line 2—2 Fig. 1.

Fig. 3 represents a transverse section on 40 line 3—3 Fig. 1. Fig. 4 represents a diagrammatic view illustrating a use of the invention.

Similar numerals of reference indicate corresponding parts in the figures.

45 Referring to the drawings,

1 designates the garment fastener, the same consisting of a body formed of a piece of wire or other suitable metal or material bent into comparatively U- or V-shape, and 50 so comprising the side arms 2 and 3 and the bend 4 joining the latter at the bottom thereof, said arms being resilient. At the top of the arm 2 is the eye 5 whose terminal 6 joins or approaches closely to the adjacent portion 55 of the side of the arm 2, so as to abut said side and so allow no passage between said

terminal 6 and said adjacent portion of the side of the arm 2 for the escape of an attachment of the brassière therethrough and consequently from said eye, hence I denominate 60 the latter as the closed eye of my garment fastener.

At the top of the arm 3 is the loop 7 whose terminal 8 which is at the bottom curled and separated or removed from the adjacent portion of the side of said arms so as to form on its lower end the throat 9 between said portion and terminal, this leading into said loop so that another attachment of the brassière may be passed through said throat and so 70 hooked on said loop 7, hence I denominate the latter as the open eye of my garment fastener.

The terminal of the loop 7 which is at the lower end thereof, as has been stated, is 75 curled to the outer side of the loop so as to prevent its raw edge from being exposed and liable to cut the one handling the fastener.

The lower portions of the sides of the arms 2 and 3 and the bend 4 are reduced in thickness and flattened in cross section as at 10, 11 and 12, so as to take firm hold of the shank of a stud 13 of a corset over which latter the brassière is worn and lie flat and closely thereon, while adding resiliency to 85 the arms to permit them to expand in slidingly riding over the shank of said stud 13 if so desired.

In the present case, I show two V-shaped straps or bands 14 and 15 which are connected with and depend from the front tabs 16 of the brassière 17, only a portion of which is shown, it being seen that the strap 14 is connected with the closed eye 5 of the fastener, hence the latter remains a fixture of 90 the strap 14 and consequently of the brassière, and will not be lost therefrom. Then the fastener is fitted on the stud 13 and the brassière adjusted on the corset when the strap 15 is hooked on the open loop 7 and so 95 100 is connected therewith, the fastening being held up by said straps engaged with the stud 13, the fastening taking firm hold of the shank of the latter, the brassière in front being properly held on the corset.

In order to remove the front of the brassière from the corset the strap 15 is disconnected from the open loop 7 and the fastener withdrawn from the stud 13 when the fastener will remain on the strap 14 pendant 110 therefrom so as has been stated it will not be lost from the brassière, while on the con-

trary it will remain thereon ready to be engaged with the stud 13 on reapplying the brassière.

I do not limit myself to the use of the fastener with the U-shaped members 14 and 15 of a brassière, as any straps, bands or the like on the latter may be attached to a fastener similar to said members, while the fastener may be employed for garments other than brassières.

For fastening other portions of a brassière, say the rear or either side, the device may be hooked on the lacing of a corset where employed and engaged with proper portions or attachments on the corset.

Having thus described my invention what I claim as new and desire to secure by Letters Patent, is:—

1. A garment fastener consisting of a comparatively U-shaped body, a closed eye on the upper terminal of one member of said body, and a loop open below terminating outside of said body and in the plane thereof on the upper portion of the other member of said body.

2. A garment fastener consisting of a comparatively U-shaped body formed of side arms, a bend member joining the bottoms of said arms, a loop open below continuous of the upper terminal of one of said side arms on the outside of and in the plane of said body, and a closed eye on the upper terminal of the other side arm.

3. A garment fastener consisting of a comparatively U-shaped body formed of

side arms, a bend member joining the bottoms of said arms, a loop open below continuous of the upper terminal of one of said side arms on the outside of and in the plane of said body, a throat intervening the terminal of said loop and the adjacent portion of the adjacent arm forming an inlet for said loop from below, and a closed eye on the upper terminal of the other side arm.

4. A garment fastener consisting of a comparatively U-shaped body, a closed eye on the upper terminal of one member of said body, and an open eye on the upper portion of the other member thereof, the sides of the bottom bend member of the arms, and the adjacent portions of said arms being of reduced thickness and made flat in cross section.

5. A garment fastener consisting of a comparatively U-shaped body formed of side arms, a bend member joining the bottoms of said arms, an eye on the upper end of one of said arms closed against the latter, and a loop on the upper end of the opposite arm with a throat intervening the terminal of said eye, and the adjacent portion of said opposite arm forming an open eye for said fastener, the sides of the bottom bend member and the adjacent portions of said arms being of reduced thickness and flattened in cross section.

CLARA V. HAVENS.
